GEORGE R. SCHROEDER, OF BEVERLY, KANSAS, ASSIGNOR OF ONE-HALF TO TEMPLE L. CAMPBELL, OF BEVERLY, KANSAS

POSTING TRAY

Application filed July 17, 1929. Serial No. 379,040.

My present invention has reference to a tray to be used in the posting of checks and deposit slips or tickets to depositor's accounts in banks, and in other businesses where items are posted to accounts in alphabetical arranged order.

My object is the provision of a posting tray which permits the checks and deposit tickets, (when used in the banking business) to be all sorted together in alphabetical order, each individual deposit ticket being sorted just beneath the check thereby permitting the operator expediting his work and insures a greater accuracy than when the checks and deposit tickets are sorted in different compartments.

A still further and important object is the provision of a posting tray divided into two compartments, one for checks and deposit slips or tickets not posted and the other for those posted and checks and deposit tickets received from the customers whose surnames begin with "A" being arranged at the top of the stack of items and those whose names begin with the letter "Z" at the bottom, while the deposit slip is arranged just beneath his check and is during the posting operation, arranged right-angularly with respect to the check, being supported upon a swingable bracket or platform so that both the check and slip or ticket can be clearly observed by the operator and thus permitting the operator to post a deposit slip or ticket immediately after posting the checks without glancing away from his work.

To the attainment of the foregoing the invention consists in the improvement herein-after described and definitely claimed.

In the drawings:

Figure 1 is a top plan view of the improvement.

Figure 2 is a front elevation thereof.

Figure 3 is a transverse sectional view therethrough.

Figure 4 is a plan view of a deposit slip or ticket.

In carrying out my invention I make use of a box-like structure 1, centrally divided by a longitudinal partition 2 into compartments 3 and 4. In the showing of the drawings the

sides of the tray have their upper ends open and have secured to the ends above the said opening and to the upper edges of the sides 4 the straight ends of arched wires 5. This permits of a full flow of light being directed into the trays provided by the compartments 3 and 4. Obviously the sides of the tray may be centrally provided with an opening in which event the wire members 5 are dispensed with. On the inner face of each of the sides 4 there is pivoted, as at 6, the angle end 7 of a shelf or tray 8. Each of the shelves or trays when not in use may be swung into the compartments of the tray and rest upon the bottom thereof and when in use as disclosed by Figures 1 and 2 of the drawings the flat shelves or brackets will rest upon the upper edges of the sides 4 of the tray. The checks and the tickets or deposit slips therefor are arranged alphabetically in the compartments provided by the tray. The checks are arranged face upwardly and the checks to be posted have their deposit slips bent and curved over the shelf or bracket as disclosed by Figures 1 and 3 of the drawings so that both the tickets or deposit slips and the faces of the checks will be clearly visible to the operator which will permit of the posting of the checks in a more expeditious and accurate manner than that usually employed. Each of the shelves has its outer end centrally formed with a substantially V-shaped slot 9 whereby the ticket or deposit slips may be drawn thereover.

It is believed the foregoing description will fully set forth the construction and advantages of my improvement to those skilled in the art to which such invention relates so that further detailed description will not be required.

Having described the invention, I claim:

A posting tray for the purpose set forth, comprising a box-like member centrally divided by a partition into spaced compartments for the reception of checks and deposit slips for said checks, the deposit slip of each check being arranged directly below said check, the outer sides of the compartments being of a less height than the tray, arched wire members secured to the ends of the tray

and to the upper edges of the sides, and terminating away from the center of said sides, a shelf having an angle end pivotally secured to each side, swingable against the bottom of each compartment and designed to have its flanged portion contact with the inner face of the outer side of the compartment and to rest and be supported on the outer edge of the said side when the said tray is swung outward of the compartment, each shelf having its outer edge notched and said shelves serving as supports for the tickets and deposit slips when the same are arranged thereover and positioned angularly with respect to the checks.

In testimony whereof I affix my signature.
GEORGE R. SCHROEDER.
